UNITED STATES PATENT OFFICE.

ROBERT H. MILLER, OF DETROIT, MICHIGAN, ASSIGNOR TO DETROIT STOVE WORKS,
OF DETROIT, MICHIGAN, A CORPORATION OF MICHIGAN.

ELECTRIC SWITCH.

1,427,312.

Specification of Letters Patent. Patented Aug. 29, 1922.

Application filed May 12, 1917. Serial No. 168,155.

To all whom it may concern:

Be it known that I, ROBERT H. MILLER, a citizen of the United States of America, residing at Detroit, in the county of Wayne and State 5 of Michigan, have invented certain new and useful Improvements in Electric Switches, of which the following is a specification, reference being had therein to the accompanying drawings.

10 This invention relates to electrical switches and refers more particularly to a new and improved switch-operating mechanism and mechanical movement therefor.

Among the objects of the invention are to 15 provide an improved and simplified switch and operating mechanism of the snap-switch type; to so construct and arrange the parts that the switch can be operated by turning the knob or handle in either direction, and 20 preferably to a plurality of different positions of adjustment when operated in either direction; to provide an improved construction in which a handle of the type such as used on gas stoves can be employed; to provide an improved and simplified mechanical movement for automatically locking the 25 switch in its various positions of adjustment; and in general to provide an improved and simplified switch and operating 30 mechanism therefor of the character above referred to.

In the drawings:

Figure 1 is a vertical sectional view 35 through an electric switch embodying my invention;

Figure 2 is a sectional plan view.

Figure 3 is a plan view showing the cam plate in a different position of adjustment;

Figure 4 is a perspective view looking 40 upward on a part of the mechanism;

Figure 5 is a perspective view of the stop plate;

Figure 6 is a view similar to Figure 3 showing the cam plate in still another position of adjustment.

Describing in detail the construction shown in the drawings, A designates the base of the switch, which base is preferably formed of hard rubber or other suitable insulating material. This base is recessed at 50 B to receive a part of the locking mechanism, leaving a circular flange C to which there is secured at various points the contact members D. The latter are provided 55 with one or more arms D' and D'' with which

there cooperate the movable contacts E and E'. There are, in the particular construction shown, two sets of these movable contacts E and E' which are formed on plates F and F'. The plates in turn are mounted between insulating washers G and G' sleeved upon the bushing H which projects through the insulator plates I and I' into the metal plate L. This plate is fixed to the bushing member H, which is loosely sleeved 60 upon the operating shaft M. The latter at its upper or outer end is provided with an operating handle M', while near its other end it is provided with a flat surface M² over which there is slidably mounted a plate N 65 spaced from the plate L by means of a spacing washer or bushing N'. Surrounding the bushing N' is a coil spring O having its opposite ends O' and O'' extending upon opposite sides of a downwardly-projecting lug L³ 70 on the plate L. An upwardly-extending lug N² preferably formed integral with the plate N also extends between the ends O' and O''. The under side of the plate N has a pin N³ 75 extending into a slot Q' in the stop plate Q, whereby the rotation of said plate and hence of the stem M is limited by contact of said pin with the ends of said slot.

As shown in Figure 5, this stop plate, in addition to the curved slot Q', has a plurality of stops Q², Q³, Q⁴ and Q⁵ positioned at 80 various points near its periphery. These stops form the part of the locking mechanism by which the switch is held in its various positions of adjustment and cooperate 85 with lugs R and R' on the cam plates R² and R³ respectively.

As shown in Figure 6 these lugs on the cam plates have shoulder portions R⁴ and R⁵ 90 which engage opposite sides of the stationary stops whenever the ends of the spring O are not under tension. These plates are each provided with elongated slots S through 95 which the shaft M extends and at their rear ends with grooves or recesses S' and S'' into which the lug L³ projects. Near their opposite ends the cam plates R² and R³ are provided with slots V and V' which have oppositely positioned enlargements V² and V³. 100

The operation of the switch and locking mechanism above described is as follows: Assuming that the handle is rotated in a clockwise direction from the position shown in Figure 2, it will carry with it the plate N 110

and as the projection N^2 extends between the ends of the spring O , it will spread apart these ends and thus tension the spring upon the initial movement. The continued movement of the handle, shaft and plate will then, through the action of the pin N^3 in the slot V , first withdraw the plate R^2 and then the plate R^3 . As soon as the plate R^3 is drawn to a position where its shoulder R^5 is out of engagement with the stop Q^3 , the cam plates and the plate L will be immediately rotated by the action of the spring end O' . As soon, however, as this spring snaps the plate L into a position where the spring ends O' and O^2 are an equal distance apart the cam plate R^2 will be forced forward so that its shoulder will strike against the next stop Q^4 . At approximately the same time the shoulder R^5 will be moved outward upon the opposite side of the stop, thus locking the cam plates from movement in either direction until after the handle is rotated. As the movable contacts E and E' are secured to rotate with the plate L the switch will be thus snapped from one position to another, and it is obvious that owing to the reversed relation of the slots in the cam plates it is immaterial in which direction the switch is rotated. Also the construction is one which can be used on electric ranges or ovens and permits the employment of a handle such as is ordinarily used in turning on a gas burner.

35 However, while the switch-operating mechanism and mechanical movement are particularly adapted for the use mentioned, the invention is not necessarily limited to such use and various other changes in the 40 details of construction and arrangements and combinations of parts can be made within the scope of my invention.

45 What I claim as my invention is:

1. In an electric switch, the combination with a base, of a stem rotatively carried by said base, a plurality of contacts rotatable about the axis of said stem, corresponding stationary contacts carried by said base and successively engageable by the 50 rotative contacts, a plate stationary upon the base having stops thereon corresponding to the stationary contacts, mechanism selectively engageable with said stops for holding the rotative contacts in their various 55 positions, said mechanism being releasable by said stem, a spring for actuating a snap

movement of a rotative contact in either direction stressed by initial rotation of the stem prior to releasing of the locking mechanism, and a pin rotatively actuatable by the 60 stem engaging in a slot of the stop-carrying plate to limit rotation of the stem in either direction.

2. In an electric switch, the combination with a base, of a stem rotatively carried by 65 said base, a plurality of contacts rotatable about the axis of the stem, corresponding contacts stationary upon the base and engageable by the rotative contacts, a spring for actuating a snap movement of the rotative contacts in either direction stressed by 70 initial rotation of the stem, a locking mechanism comprising a series of stops corresponding to the several circuit closing positions of the rotative contacts, and a pair 75 of cam plates respectively having shoulders for engagement at opposite sides of one of said stops, and connected to said rotative contacts, a means actuatable by rotation of said switch, subsequent to stressing of said spring, to successively withdraw said cam plates from the engaged stop, and thereby permit actuation of the rotative contacts by the spring.

3. In an electric switch, the combination 85 with a base, of a stem rotatively carried by said base, a plurality of contacts rotatable about the axis of the stem, corresponding contacts stationary upon the base and engageable by the rotative contacts, a spring 90 for actuating a snap movement of the rotative contacts in either direction stressed by initial rotation of the stem, a locking mechanism comprising a series of stops corresponding to the several circuit closing positions of the rotative contacts, and a pair 95 of cam plates respectively having shoulders for engagement at opposite sides of one of said stops, and connected to said rotative contacts, said plates respectively having cam slots, and a pin rotative with the stem engaging in the slots of both of said plates, for withdrawing said plates from the engaged stop subsequent to stressing of said spring and thereby permitting actuation of 100 the rotative contacts by the spring.

In testimony whereof I affix my signature in presence of two witnesses.

ROBERT H. MILLER.
